[57] **CLAIM**

The ornamental design for a compression fitting for a weed-killing wick applicator, as shown and described.

DESCRIPTION

FIG. 1 is a top perspective view of a compression fitting for a weed-killing wick applicator, showing our new design;

FIG. 2 is a left elevation thereof mounted on a reservoir represented in broken lines for illustrative purposes only;

FIG. 3 is a front elevation thereof;

FIG. 4 is a top plan view thereof;

FIG. 5 is a bottom plan view thereof;

FIG. 6 is an exploded left and elevation thereof;

FIG. 7 is a top plan view of the compression fitting body element, shown separately for clarity of illustration; and

FIG. 8 is a bottom plan view thereof.
